(74) *Attorney, Agent, or Firm* — Andrew C. Cheng

(57) **CLAIM**

The ornamental design for a faucet, as shown and described.

DESCRIPTION

FIG. 1 is a front perspective view of a faucet showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view thereof, showing the faucet in a state of use; and,

FIG. 10 is an enlarged view of circled portion 10 of FIG. 8. The broken lines in the drawings depict portions of the faucet that form no part of the claimed design.

1 Claim, 10 Drawing Sheets
